[57] CLAIM

The ornamental design for a combined facsimile transceiver and copying machine, as shown and described.

DESCRIPTION

FIG. 1 is a top, front and right side perspective view of a combined facsimile transceiver and copying machine showing our new design;

FIG. 2 is a front elevational view thereof;

FIG. 3 is a rear elevational view thereof;

FIG. 4 is a top plan elevational view thereof;

FIG. 5 is a right elevational view thereof;

FIG. 6 is a left elevational view thereof;

FIG. 7 is a bottom plan view thereof; and,

FIG. 8 is a top, front and right side perspective view thereof, shown with the cover in an open position and the paper cassette pulled out.

FIG. 1

FIG. 2

FIG. 3

FIG. 4

FIG. 5

FIG. 6

FIG. 7

FIG. 8
